FOUNDATION GARMENT

Katherine E. Cunningham, New Haven, Conn.,
assignor to I. Newman & Sons, Inc., New
Haven, Conn., a corporation of Connecticut

Application March 28, 1933, Serial No. 663,210

1 Claim. (Cl. 2--30)

This invention relates to foundation garments and has for an object to provide an improved construction wherein there is presented a brassière structure and a corset structure merging 5 slightly above the waistline with the parts so formed that each part will function in a desirable way without objectionably affecting the other parts.

Another object of the invention is to provide 10 an improved foundation garment wherein the corset portion is provided with an arrangement of elastic panels and gores whereby a desirable spreading action is permitted when the person wearing the garment bends or sits down.

Another object of the present invention is to 15 provide in a foundation garment means substantially at the waistline for bracing the back and at the same time producing a desired tension at the front of the garment in a way to hold the brassière in proper operating position and also to 20 cause the corset portion to efficiently support the front part of the body.

In the accompanying drawing:—

Figure 1 is a perspective view of a foundation 25 garment disclosing an embodiment of the invention, the same being shown on a figure;

Figure 2 is a rear perspective view of the garment shown in Figure 1, the same being illustrated on a figure;

Figure 3 is an elevation of the foundation garment spread out;

Figure 4 is an enlarged sectional view through Figure 3, on the line 4—4.

Referring to the accompanying drawing by numerals, 1 indicates the corset or corset body, and 2 the brassière which merges into the corset body substantially at the waistline. The corset body is provided with a front 3 and a back 4. The front 3 is formed from front side panels 5 and 6 and a central panel 7 which tapers substantially from the waistline to the bottom of the garment and is constricted above the waistline and merges into the brassière. The extension 8 of the front 7 acts to hold the breast pockets 9 and 10 properly 40 in place and in a way to properly function for supporting the breasts when the garment is in use. The front side panels 5 and 6 are also provided with the brassière extensions 11 and 12, to which the breast pockets are secured. It will 45 be understood that the breast pockets are secured along their sides and bottom edges so that a pull on the corset body at the waistline will also give a desired tension to this part of the brassière.

The front side sections 5 and 6 at the lower 50 ends are provided with chamfered edges 13 and 14

which with the tapering of the section 7 presents gore-shaped openings in which the elastic members 15 and 16 are positioned. This gives a yielding action to the front, though ordinarily these parts are so proportioned as to contract the front and bow the same inwardly when the corset is upright as illustrated in Figure 1. However, when the person wearing the corset sits down, this part will spread and in addition the side elastic panels 17 and 18 will also spread or yield resiliently. All of these elastic panels taken with the front 3 and rear 4, act to mold the parts of the body arranged adjacent thereto, and yet by the arrangement just described present a structure which will yield when necessary. The rear 4 is 15 provided with any desired number of reinforcing members 19 which may be in the nature of ordinary stays and pockets, said stays and pockets extending from the bottom to the top of the corset body.

The corset body extends slightly above the waistline which line is approximately centrally of the strap 20. The rear section 21 of the brassière 2 is connected to the top edge of the rear 4 and together with the front part of the 25 brassière is supported by desirable shoulder straps 22 and 23. The strap 20 is made of some strong piece of cloth and is held permanently at the rear 4 by stitching 24. This stitching is arranged so that the strap has free tabs or ends 30 25 and 26. To these free ends are arranged elastic members 27 and 28. The elastic structure 28 is connected to the front side panels 6 by a line of stitching 29 while the elastic member 28 is 35 connected by lines of stitching 30 to the edge panel 31 which edge panel carries loops or other form of disengageable fastening means 32. The edge of panel 5 also carries disengageable fastening means which are adapted to interlock 40 with the fastening means 32. These fastening means may be of any desired kind, as, for instance, ordinary hooks and eyes. It will be noted that the garment is open at the side from the top to the bottom and is, in effect, a wrap-around structure, but by reason of the various elastic members set forth, including members 45 27 and 28, a snug fit is secured which will not be uncomfortable but which will mold the body somewhat and by reason of the strap 20 the elastic members 27 and 28 and associated parts 50 will produce a desired tension on the front of the garment, said tension being transmitted to the center of the rear of the garment substantially at the waistline.

I claim:

A foundation garment including a corset body and a brassière having breast pockets, said brassière merging into the top of the corset body, 5 said corset body and brassière being open from top to bottom along one side, said corset body having a substantially inelastic front, an inelastic back and a pair of elastic side panels extending from the top to the bottom of the corset body,

a bracing strap confined below said breast pockets and attached to the corset body adjacent the forward edges of the respective elastic panels and acting to constrict the waistline and uplift the breasts of the person wearing the garment, 5 said bracing strap having elastic and inelastic portions and means for connecting said strap to said inelastic back substantially centrally thereof.

KATHERINE E. CUNNINGHAM.
